UNITED STATES PATENT OFFICE.

GEORGE GODFREY BELL, OF PROVIDENCE, RHODE ISLAND.

KEY-CHAIN REEL.

1,262,005.

Specification of Letters Patent. Patented Apr. 9, 1918.

Application filed December 17, 1917. Serial No. 207,488.

To all whom it may concern:

Be it known that I, GEORGE GODFREY BELL, residing at Providence, in the county of Providence and State of Rhode Island, 5 have invented a new and useful Improvement in Key-Chain Reels, of which the following is a specification.

In the usual construction of key-chains, the chain has a key-ring on one end to which 10 the keys are secured and on the other end a wire loop for securing the chain to a button on the clothes. The chain must be sufficiently long so that the keys may be brought into a convenient position for use. Usually 15 the bunch of keys are held in a rear pocket when not in use and the chain hangs downward from the button and pocket in a long loop. The key-chain when thus used is unsightly and in the way, the looped chain 20 is liable to become caught on stationary objects, in moving about, thereby jerking the keys out of the pocket or pulling the button off the clothes, or both.

The object of my invention is to provide a 25 key-chain with a spring actuated reel adapted to wind the chain up on the reel, thereby eliminating the looped chain, the use of a pocket for the keys, which wear out the pocket, and other undesirable features.

30 A further object of my invention is to provide a key-chain and ring with a key-chain reel having a casing, a spring actuated reel in the casing to which the inner end of the chain is secured, means on the back of the 35 casing for detachably and pivotally securing the reel to a button on the wearing apparel and means on the front of the casing for detachably securing the key-ring with the keys, to the casing.

40 My invention consists in the peculiar and novel construction of a key-chain reel, said key-chain reel having details of construction, as will be more fully set forth herein-after and claimed.

45 Figure 1 is a side view of the body portion of a man showing the key-chain reel attached to a suspender button over the rear pocket, with the chain drawn out so as to bring the keys into a convenient position for 50 use, in full lines, and with the keys drawn back next to the reel, when not in use, in broken lines.

Fig. 2 is a front view of the key-chain reel.

Fig. 3 is a back view of the key-chain 55 reel, and

Fig. 4 is an enlarged view partly in section, taken on line 4. 4 of Fig. 2, and showing the reel attached to a suspender button on the clothing. 60

In the drawing 3 indicates the waist band of a pair of trousers, 4 a suspender button, 5 a key-chain, 6 a key-ring secured to the outer end of the chain, and 7 my improved key-chain reel. The key-chain 5 and key-ring 6 may be of any well known construction. 65

The reel 7 consists of a flat circular casing of sheet metal having the central bearings 8. 8 in the front and back, a chain opening 9 in its edge, a spring hook 10 on its front and a button attaching spring strap 11 secured at one end to the back of the casing. This strap 11 has a button hole opening 12 in the shape of an inverted key-hole in its free end, with the contracted part 70 of the opening toward the free end of the strap. The fixed end of the strap is shaped to lie flat to the back of the casing. The rest of the strap is shaped to have an out- 75 ward bend 13, a straight portion 14 parallel with the back, an outward bend 15 on approximately a line with the center of the button hole opening 12 and a straight free end portion 16 parallel with the back of the 80 casing, when in use, as shown in Fig. 4. A reel 17 in the casing has a shaft 18 rotatably supported in the bearings 8. 8 in the casing and a helical spring 19 in the casing has one end secured to the shaft 18 and the 85 other end secured to a pin 20 in the casing. The inner end of the key-chain 5 extends through the chain opening 9 in the casing and is secured to the reel 17 on which it is wound up by the spring 19. The outward 90 bend 15 across the button hole opening 12 allows a free entrance to the button, with the spring strap 11 sprung back toward the casing, which is its normal position. The 95 reel is attached by placing the reel in a position for the button to enter the button hole opening 12 in the strap 11 and then pulling downward on the reel. This forces the button upward between the spring strap and the back of the casing with the shank of the 100 button in the upper end of the contracted portion of the button hole opening, as 105 shown in Fig. 4. The button is now held

frictionally between the back of the reel and the spring strap and the shank of the button forms a pivot for the reel. When it is necessary to use the keys, the keys and chain are pulled outward to bring the keys into a convenient position for use, as shown in full lines in Fig. 1, the reel pivoting on the shank of the button so as bring the chain opening in the reel on a line with the pull 10 of the chain. This unwinds the chain from the reel and winds up the reel spring. When not in use the reel winds up the chain on the reel in the casing and the keys may hang suspended from the reel, as shown in 15 broken lines in Fig. 1, or the keys may be hung by the key-ring on the reel hook 10 on the reel.

It is evident that any equivalent of the key-chain 5 could be used and the reel could 20 be pivotally and detachably secured to a button or similar device, in any position desired on the person.

Having thus described my invention I claim as new:

25 1. A key-chain reel comprising a casing, a spring actuated reel in the casing, a key-chain extending through a hole in the casing and secured to the reel, on which it is wound, a key-ring on the outer end of the 30 key-chain, a hook fixed at one end to the front of the casing and a strap on the back of the casing, said strap being secured at one end to the casing and having a button 35 hole opening adjacent its free end and an outward bend at each side of the button-hole opening, whereby the free end of the strap is held away from the back of the casing, for the purpose as described.

2. A key-chain reel comprising a casing, a spring actuated reel in the casing, a key-chain extending through a hole in the edge 40 of the casing and secured to the reel, on which it is wound, and spring strap secured at one end to the back of the reel and having a button-hole opening in the shape of 45 an inverted key-hole, adjacent the free end, an outward bend adjacent its fixed end, a straight portion, an outward bend at each side of the button hole opening and a straight free end portion, and a spring hook 50 on the front of the casing, for the purpose as described.

3. A key-chain reel comprising a circular casing having central bearings in the front and back and a chain opening in its edge, 55 a spring hook on the front of the casing, a button attaching spring strap secured at one end to the back of the casing, and having a button-hole opening in the form of an inverted key-hole, in its free end, an outward bend adjacent the fixed end, a straight portion, an outward bend at each side of the button-hole opening and a straight free end portion, a reel in the casing and having a 60 shaft rotatably supported in the bearings in the casing, a helical spring in the casing and having one end secured to the reel shaft and the other end secured to a pin in the casing, and a key-chain extending through 65 the chain opening in the casing and secured to the reel, on which it is wound, whereby the reel is pivotally and detachably secured to a button on wearing apparel.

In testimony whereof, I have signed my name to this specification.

GEORGE GODFREY BELL.
